UNITED STATES PATENT OFFICE.

ROBERT LUNDELL, OF NEW YORK, N. Y.

PROJECTILE.

1,384,841.

Specification of Letters Patent. Patented July 19, 1921.

Application filed June 17, 1918. Serial No. 240,423.

To all whom it may concern:

Be it known that ROBERT LUNDELL, a citizen of the United States, and resident of New York city, in the county of New York and State of New York, has invented certain new and useful Improvements in Projectiles, of which the following is a specification.

This invention relates to projectiles or shells particularly adapted for naval warfare, the chief object being to provide a projectile of this type which will strike an object below the water level as well as at or above it. In this manner, the effectiveness of the projectile is considerably increased as it is capable of striking a part of the target, such as a ship, which is below the water level and, therefore, not protected by armor and, consequently, extremely vulnerable. The projectile is, moreover, especially adapted for use against submarines or other craft which present little freeboard. To attain the above mentioned object, the projectile has to be prevented from ricocheting upon a surface of water when fired at a low angle of elevation and the resistance offered by the air and the water to the flight of the projectile must be kept within practicable limits.

A further object of the invention is to provide a high velocity projectile which will 30 permit the twist of the rifling of the gun-barrel from which it is discharged to be reduced or kept within practical limits and this is effected by constructing the same in such manner that its speed of rotation will 35 be increased or affected in a desirable manner during flight. Still another object is to provide a projectile with means for effecting a proper spin thereof during flight in combination with means effecting stabilizing of 40 the projectile when fired from a smooth bore gun.

It is well known that the ordinary shell will ricochet when striking a surface of water at a comparatively small angle unless 45 the shell is provided with a specially cup-shaped or square nose, in which case the resistance offered by the air or the water is materially increased which, of course, seriously interferes with the effective range 50 of the shell. It is also well known that in order to prevent a projectile from tumbling or keyholing, it is necessary to impart thereto a considerable speed of rotation, to insure sufficient stability by reason of gyroscopic 55 action. It is also known that the speed of rotation has to be increased with an increase

in the length relative to the diameter of the projectile, so that, with modern projectiles having a length of about 4.5 times the caliber, the twist of the rifling is equal to one 60 complete turn for a barrel-length of only about 25 calibers. The twist of such rifling is considerable and the problem of preventing stripping of the driving band or bands and rapid deterioration of the rifling in the 65 gun-barrel presents serious difficulty.

For a clear understanding of my invention, reference is made to the accompanying drawings, in which:

Figure 1 represents a longitudinal section 70 of a projectile embodying my invention;

Fig. 2 is a cross-sectional view taken on the line 2—2 of Fig. 1;

Fig. 3 shows in longitudinal section the forward portion of another form of my improved projectile whereof the construction is particularly conducive to increasing the speed of rotation of the projectile after it has left the gun-barrel.

Fig. 4 is a cross-sectional view taken on 80 the line 4—4 of Fig. 3;

Fig. 5 shows in longitudinal section of another form of shell with which my invention may be used.

Referring to the drawings, Figure 1 shows 85 a shell or projectile substantially ordinary construction furnished with a driving band 5 and arranged to receive the usual type of base-fuse or base-detonator which screws into the threaded portion of the shell at 6. 90 The forward end of the shell differs slightly from the ordinary construction in that the shell has a threaded portion at 7 and a slight contraction at 8 of the filling chamber. 9 95 represents a steel tube or attachment provided with a considerable number of spiral openings or slots 10 and connecting ribs 13 between the said slots. The steel tube 9 is accurately fitted over the pointed portion of the shell as clearly shown in the drawing. 100 The slots 10 are cut in the middle portion of the steel tube and are so beveled or shaped at the ends that a minimum resistance is offered to either air or water during the flight of the projectile. Said slots are 105 furthermore so proportioned in regard to their length, width and number that the air or the water is provided with an exit-area through these slots substantially equal to the entrance-area contained within the 110 forward cylindrical portion of the steel tube. Upon striking a sheet of water the

chisel-shaped forward edge of the steel tube will immediately bite or cut into the water and the cylindrical portion of the tube will serve as a tubular rudder causing the projectile to keep to its true trajectory until the speed of the same is very much reduced by the resistance of the water. It will be readily appreciated that, if there were no outlets provided in the steel tube, the air or water contained within the tube would be under great pressure on account of the high speed of the projectile and considerable resistance would be offered to its travel. Even with adequate outlets there will still be considerable pressure from the air or the water within the tube but in the preferred form of my invention this pressure of the fluid is utilized to affect the rotary motion of the projectile. The pitch of the slots shown in the drawing corresponds approximately to about one turn in twenty calibers. Assuming that the shell is fired from a gun having a moderate twist of rifling of one turn in thirty calibers the air or water pressing through the tube 9 and being forced outwardly by the pointed portion of the projectile, will exert a greater pressure upon the edges 11 than upon the opposite edges of the ribs 13, thereby tending to cause the projectile to gradually increase its speed of rotation until it approximates one turn in twenty calibers. The above description applies in a general way to the construction shown in Figs. 3 and 4. Instead of the steel tube 9 and Fig. 1 a machined steel casting or a die casting is used, which consists of a conical central portion 13 and numerous leaf-like ribs or blades 14 connecting said central portion to an outer tubular or cylindrical portion 15 as clearly shown in the drawings. It will be seen that the steel casting is attached to the shell substantially like the steel tube in Fig. 1. It may, however, be attached in many different ways, in fact, the central conical portion 13 may be attached to the shell like the well known soft steel cap used for armor-piercing projectiles and it may even serve the same purpose. As the steel casting in Fig. 3 is more elaborate than the simple steel tube in Fig. 1 it has to be carefully machined and balanced for rotation. However, it has the advantage that the blades 14 will exert a far more powerful rotary force than the ribs 12 in Fig. 1 and will quickly increase the speed of rotation of the projectile after it has left the gun. It will be noticed that the greater portions of these blades are spread out at the periphery of the casting, so that maximum leverage or torque for the rotary motion is obtained. The blades are also placed in a position (relative to the body of the projectile) where the air or water is under the greatest compression. Attention may here be directed to the fact

that various types of bombs and slow speed bullets or projectiles fired from smooth bore guns, are usually furnished with fan-shaped tails or propeller-blades in order to prevent tumbling or wobbling motion. Such devices are effective mainly because they serve to place the center of gravity of the bullet or the projectile well forward. The rotary effort from a propeller-shaped tail-piece applied to a high speed projectile would, however, be insignificant because the device would travel in a rarefied atmosphere which would produce relatively little turning movement. Hence the importance of my invention is in placing the turning arrangement at the forward end of the projectile. As shown in Figs. 1 and 3 the tubular ribs 9 and 15 are relatively light in weight as compared with the body portion of the projectile. This is important in order that they offer little resistance and do not materially alter the ballistic characteristic of the projectile. Also the spiral blades or members are much longer in the axial direction of the projectile than in their radial direction in order to obtain maximum torque.

With certain ballistic proportions such as indicated in Fig. 5 it is possible to further reduce the twist of the rifling in a gun-barrel. The projectile shown in Fig. 5 has an exceptionally heavy head as shown at 16 and the base of the projectile is made exceptionally light by means of the tubular extension 17. This type of projectile, having its center of gravity far forward, has less tendency to wobble after being fired than the ordinary type and will quickly increase its stability in the air when furnished with the style of diving-cap shown in Fig. 105 3. Other means attached to the fuse-block 18 may in certain cases be preferable to the tubular extension 17. By using a projectile of this type having a reduced length relative to its diameter, the rifling of the gun barrel may be entirely dispensed with and the projectile may advantageously be fired from a smooth bore gun, the main point being to shift the center of gravity of the shell far enough forward to insure sufficient 110 initial stability until the requisite speed of rotation is attained by means of the blades 15 or the like. A diving-shell or a torpedo-shell of the type described will naturally be very effective in a naval engagement in that 115 it will readily reach the vulnerable portions of an armored ship below the water line. When fired at a submarine which is just awash or with only the conning-tower or periscope showing the chances of scoring an 120 effective hit will be considerably increased.

I wish it to be understood that I do not limit my invention to the specific constructions shown as various modifications in the design could be made and the invention em- 130

bodied in small arms projectiles and other widely differing forms without departing from the main features of the invention. Although Figs. 1 and 3 both show detachable diving-caps, such construction is not essential unless different qualities of metal are to be employed.

I claim:

1. A projectile having a reduced head and a diving-device to prevent ricochetting consisting of a tubular member surrounding and extending forward of said reduced head and being connected with the body portion of the projectile by a plurality of spiral members between which open ports are formed for the escape of air or water which has entered the mouth of said tubular member during the flight of the projectile, said open ports having a combined cross-sectional area substantially equal to or greater than the area inclosed by the mouth of said tubular member.

2. A projectile having a reduced head and a diving-device to prevent ricochetting consisting of a tubular member surrounding said reduced head and a plurality of spiral members, between which open ports are formed, for connecting said tubular member to a base-member, the latter being secured in a detachable manner to the body portion of the projectile and said open ports having a combined cross-sectional area substantially equal to or greater than the area inclosed by the mouth of said tubular member.

3. A projectile having a reduced head and means for engagement with the rifling of the gun-barrel from which the projectile is discharged to give an initial spin to the projectile, a tubular member surrounding said reduced head to prevent ricochetting and for receiving air or water under pressure during the flight of the projectile and helical members of greater twist than the rifling of the gun-barrel for utilizing the pressure of said air or water to increase the spin of the projectile after firing, open ports being formed between said helical members and said ports having a combined cross-sectional area substantially equal to or greater than the cross-section of the body portion of the projectile.

4. A projectile having a heavy and pointed forward portion and a comparatively light rear portion, a tubular member extending about the said forward portion and being spaced therefrom, said tubular member being relatively light in weight as compared with the body portion of the projectile, and a plurality of spiral blades of substantially uniform twist throughout their entire length for rigidly securing the tubular member to the body portion of the projectile.

5. A projectile having an annular rim extending forward of the head end of the projectile and being spaced therefrom, said rim being of substantially the same diameter as the body portion of the projectile and being connected therewith by a plurality of spiral blades of substantially uniform twist throughout their entire length, lateral ports being formed between said blades for the escape of air or water which has entered the mouth of said rim during the flight of the projectile.

6. A projectile having a pointed head portion and a diving head comprising a tubular metal rim spaced from and surrounding the pointed portion of the projectile and of substantially the same diameter as the projectile, and a plurality of blades connecting said rim with the projectile, and forming open ports between said blades for the escape of the air or water which has entered the mouth of said rim during the flight of the projectile.

7. A projectile having a pointed head and a tubular member relatively light in weight as compared with the body portion of the projectile, said tubular member extending over the pointed head and being connected with the body portion of the projectile by a plurality of spiral blades between which exit areas are formed for the air or water confined by the tubular member, said exit areas being at least substantially equal to the cross-section of the body portion of the projectile.

Signed at New York city, in the county of New York and State of New York this 15th day of June, A. D. 1918.

ROBERT LUNDELL.
